[57] CLAIM

The ornamental design for a toilet seat lifter, or the like, substantially as shown and described.

DESCRIPTION

FIG. 1 is a perspective view taken from the top, front and right side of a toilet seat lifter or the like showing my new design;

FIG. 2 is a right side elevational view thereof;

FIG. 3 is a top plan view thereof;

FIG. 4 is a front elevational view thereof;

FIG. 5 is a left side elevational view thereof; and

FIG. 6 is a rear elevational view thereof.

FIG. 1
